UNITED STATES PATENT OFFICE.

WILLIAM E. MOORE, OF PITTSBURGH, PENNSYLVANIA.

ELECTRIC REGULATOR.

1,378,971.

Specification of Letters Patent. Patented May 24, 1921.

Application filed November 16, 1918. Serial No. 262,805.

To all whom it may concern:

Be it known that I, WILLIAM E. MOORE, a citizen of the United States, residing at Pittsburgh, in the county of Allegheny and State of Pennsylvania, have invented certain new and useful Improvements in Electric Regulators, of which the following is a specification.

My invention relates to improvements in electrical regulators, and it consists in the combinations, constructions and arrangements herein described and claimed.

An object of my invention is to provide a device which may be used in connection with prime movers, electric furnaces, electric circuits, etc., for automatically controlling the same, and in which the instant starting or stopping of the controlling or regulating motor may be effected without overrunning or hunting.

A further object of my invention is to provide an electric regulator which is relatively simple in construction, and which is provided with auxiliary manual controlling means which may be worked in conjunction with the automatic control without interference.

A further object of my invention is to provide an automatic regulating device for regulating the length of the arc in an electric furnace.

Other objects and advantages will appear in the following specification, and the novel features of the invention will be particularly pointed out in the appended claims.

My invention is illustrated in the accompanying drawings, forming part of this application, in which—

Figure 1 is a diagrammatic view showing one embodiment of my invention; and

Fig. 2 is a similar view showing a modified form.

In Fig. 1, I have shown, diagrammatically, an arrangement by means of which the flow of water to a water wheel in an electric generating plant may be governed. In the drawings, I indicate a fly-ball governor of the ordinary kind, which may be connected with the water wheel (not shown). This governor actuates a walking beam or lever 2, which is pivoted at 3, and which is provided with a contact 4 arranged to engage upper and lower contacts 5 and 6 respectively, depending upon the speed of the water wheel, and the posi-

tion of the ball governor. The closure of the contacts 4 and 5 is designed to energize a magnet 7, while the closure of the contacts 4 and 6 is designed to energize a magnet 8 in the manner hereinafter explained. The magnet 7 controls a single pole double throw switch S, the arms of which bear contacts 9 and 10 respectively, the former arranged to engage a stationary contact 11, and the latter adapted to engage a stationary contact 12. One arm of the switch S is provided with a spring 13 which keeps the contacts 10 and 12 closed when the magnet 7 is deenergized. The energization of the magnet 7, however, causes the closing of the contacts 9 and 11 and the opening of the contacts 10 and 12.

The magnet 8 controls a switch S' which is similar to the switch S, the parts 9' to 13' inclusive corresponding to the parts 9 to 13. A control or winding motor 14 which would be connected on to the means for regulating the source of water supply, as for instance the gate of a turbine water wheel, may be provided with any suitable mechanism for operating the gate, this mechanism being shown diagrammatically at 15 and 16.

In a direct current power plant, the water wheel would, of course, be connected with a direct current generator, and the latter might be used as the source of current for actuating the control or winding motor 14, but I prefer to use a separate motor-generator set, since the latter is always available, even in case the main power generator should, for any reason, be put out of commission. The motor generator set consists of a direct current generator 17 driven by a motor 18, which may be a direct current motor, or of the ordinary induction polyphase motor type, or any other type of motor. On the shaft connecting the motor to the generator there is preferably placed a fly wheel 19 which stores sufficient energy so that in case of interruption to the power supply 20 the fly wheel will be able to supply sufficient stored energy through the generator 17 to carry the winding mechanism 15 and 16 through one-half or more complete cycles for opening or closing the gate or valve controlling the flow of power through the prime mover.

When utilizing an automatic regulating device of this kind, there is a possibility of

overrunning or hunting, that is to say, the winding motor may operate the winding mechanism too far in one direction before the automatic speed governor can function 5 to stop the motion. In order to allow rapid motions of the winding gear, it is, therefore, very desirable to provide anti-hunting means. This may be accomplished by applying a reactive force to the speed gov-10 ernor, tending to open circuit after the same has been established. To accomplish this purpose, there are incorporated in this regulator two solenoids 42 and 43, acting on the solenoid cores attached to an extension 15 2^x of the walking beam 2. These solenoids are connected across the armature of the winding motor 14 in such manner as to receive an impulse proportional to the speed thereof, as hereinafter set forth.

20 The operation of the apparatus thus far described is as follows: Assuming that the speed of the prime mover or water wheel is decreasing, it is obvious that the ball governor 1, in lowering, would cause 25 the walking beam 2 to move so as to eventually close the contacts 4 and 5. This energizes the magnet 7, the energizing circuit being from the generator 17, through the switch arm 21, conductors 22, 23, 24, 30 walking beam 2, contacts 4 and 5, conductor 29, magnet 7, conductor 30, 31, switch arm 32, and by 33 to generator. The magnet 7, being energized, closes the contacts 9—11, and opens the contacts 10—12 of the switch S. 35 This completes a circuit through the motor 14, from the generator 17 through switch arm 21, 22, resistors 34^a and 34^b, contacts 11 and 9, conductor 35, motor 14, 36, contacts 10' and 12', resistor 37^a, conductor 31, 32 40 and 33 to generator. In the present instance, the motor 14 is shown as being provided with a shunt field 38, the energizing circuit of this field being from the generator 17, switch arm 21, 22, 23, coil 38, conductor 39 45 to conductor 31 and back to the generator by the path already traced. The operation of the motor 14 regulates the gates and causes an increase (in the present example) in the power supply, thus speeding up the 50 prime mover.

When the governor 1 has been increased in speed to the point where its fly-balls will rise and break the contacts 4 and 5, then the magnet 7 is deenergized, the spring 13 causes 55 the reverse movement of the switch S, closing the contacts 10 and 12, and opening the contacts 9 and 11. The effect of this is to short circuit the armature of the motor through the resistors 37^a and 37^b, thus applying 60 a dynamic brake to bring the winding mechanism to an instant stop, tending to reduce overrunning or hunting.

To insure the prompt stopping of the winding motor 14, however, I provide the 65 solenoid 43, which is connected across the

armature of the motor as shown in the drawing, and which receives an impulse proportional to the speed of the motor over the following path: from the motor 14, through conductor 35, conductor 35', solenoid 43, 70 conductor 45, contacts 12'—10', and by conductor 36 to motor. The solenoid modifies the action of the governor 1, i. e., it tends to break the circuit at the contacts 4—5 before it would ordinarily be broken by the 75 governor, were the solenoid not present. The force exerted by the solenoid is not sufficient of itself to overcome the action of the governor, but it is designed so that it will act at the time desired to prevent the 80 motor from overrunning.

Should the speed of the prime mover continue to increase to the point where the governor 1 would shift the contact 4 into engagement with the contact 6, then the magnet 8 would be energized, the energizing circuit being to the contact 4 over the path already traced in connection with the magnet 7, thence through contact 6, conductor 40, magnet 8, 41, and back to the generator 85 over the path previously traced. The energization of the magnet 8 causes the closing of the contacts 9' and 11', and the opening of the contacts 10' and 12'. Current now flows from the generator 17 through 21, 22, 34^a, 11', 9', switch S', 36, motor 14, 35, switch S, 10, 12, 37^b, 31, 32, 33 and back to generator, thus reversing the direction of rotation of the motor 14 and causing the winding mechanism to close the gates to cut down the 95 power flow.

As the prime mover slows up, due to the decrease of power flow, the contacts 4 and 6 are broken, the switch S' is retracted by the spring 13' to its normal position, and 105 the armature of the motor 14 is again short circuited through the resistors 37^a and 37^b, again applying the dynamic brake so as to bring the winding mechanism to an instantaneous stop. This action is made certain 110 by the solenoid 42 which operates in the same manner as described in connection with solenoid 43.

In Fig. 2, I have shown an arrangement by means of which the length of the arc in 115 an electric furnace may be automatically regulated, as well as means for accomplishing such regulation manually, if desired. In this figure the electric furnace is shown diagrammatically at 46, the electrode 47 being raised or lowered by means of the winding motor 14 through mechanism 48 including the cable 49. It will be understood that this raising or lowering mechanism is illustrated in a purely dia- 120 grammatic form, and that other means than that actually shown might be used without departing from the spirit of the invention. The electrode 47 is fed by a circuit running 125 through a current transformer 50 to the 130

power transformer 51, or other suitable source of supply. The current transformer 50 energizes a solenoid 52 which, through its plunger 53, operates the walking beam 5 2, the weight of the plunger being partially balanced by means of a spring 54. The arrangement is such that when the solenoid 52 is energized, the plunger 53 moves upwardly, thus tending to lower the opposite 10 end of the walking beam. When the solenoid is deenergized the contacts 4 and 5 are closed, being biased to this position by the weight of the plunger 53. When the furnace conditions are normal, the solenoid 52, assisted by the spring 54, equals the force 15 due to the weight of the plunger 53 in such a way as to open both contacts 4-5 and 4-6. In order to adjust the apparatus for a variation in the current through the electrode 20 circuit, a dial rheostat 55 is shown, connected in parallel with the wires 56 and 57, in such a manner as to shunt a portion of the current developed in the transformer 50 through the rheostat, thus sending only 25 a portion of the current to the solenoid 52. The rheostat 55 is located in convenient range of the machine being regulated, which, in the present instance, is the electrode in the electric furnace, so that the operator may 30 vary the current and therefore the flow of power, as desired.

In order to provide for manual regulation, I may use a drum switch. In Fig. 2 I have shown this drum switch as a diagrammatic 35 development. Thus the surface of the drum may be provided with contacts 58, 59, 60, 58', 59' and 60' which are relatively short, while the contacts 61, 61', 62, and 63 are longer. A series of contact buttons 64 to 68 inclusive, and 64' to 68' inclusive, are provided. 40 on a stationary frame. (Not shown.) The lines α - α indicate the different positions of the drum and its contacts with respect to the stationary contacts. The normal position 45 of the drum is that shown in Fig. 2. In this position a conductor 69, which connects the contacts 58 and 58', forms part of the automatic regulating circuit.

It will be observed that there is an automatic no voltage relay or circuit breaker 50 70, which is controlled by the transformer 51, and which, as long as the transformer is active, completes a circuit from the conductor 23, which leads from the generator 55 17 to the contact 64', by means of the wire 71.

Let us assume that the current flow decreases below normal, as, for instance, when the electrode 47 burns away and the arc becomes too long. Then the walking beam 60 2, owing to the reduced pull of the solenoid, may close the contacts 4 and 5, thus energizing the magnet 7, the energizing circuit being as follows: from the generator 17, through 21, 22, 23, 72, 70, 71, 64', 58', 69, 65 64, 58, 24, 2, 4, 5, 29, magnet 7, 30, 41, 31, 32, 33 to generator. The actuation of the magnet 7 closes the contacts 9-11 and opens contacts 10-12, thus energizing the winding motor 14 over the circuit already traced in connection with Fig. 1. This tends to 70 lower the electrode 47 and to shorten the arc to normal.

When the current increases in the electrode circuit the solenoid 52 may cause the closure of the contacts 4 and 6, and in such 75 event the magnet 8 is energized, and the switch S' is operated to effect the reversal of the direction of rotation of the winding motor 14, thus raising the electrodes. These operations are repeated to adjust the resistance of the electrode circuit to such a point 80 as will maintain the current in the electrode circuit at the desirable limit for which the apparatus is adjusted. In this case, as in the case of the walking beam shown in Fig. 85 1, the solenoids 42' and 43' are connected across the terminals of the winding motor 14 in order to prevent hunting or overrunning.

Referring now to the manual means of 90 control, it will be noted that there are seven positions. The central position is the "automatic," or the position in which the drum is placed to permit the automatic regulation described above, the conductor 69 forming 95 part of the circuit through the contacts 64 and 64'. Consider now a movement to the right or left to the positions marked "off." In either case the contacts 58 and 58' will move so as to break the circuit, thus rendering both the automatic and the manual control ineffective. If it should be desired to lower the electrode, the drum switch is moved to the right in Fig. 2. Let us assume that it is moved to the position marked 100 "hand 1." The following contacts are engaged: 61 with 65, 62 with 67' and 63 with 68'. Current now energizes the magnet 7 over the following path, from the generator 17, through 21, 22, 23, 75, 67', 62, 59, 61, 65, 110 76, 29, magnet 7, 30, 41, 31, 32, 33, to generator. The closing of the contacts 9 and 11 forms an energizing circuit for the winding motor 14, from the generator 17, through 21, 22, resistors 34^a and 34^b in series, 11, 9, 35, 115 motor 14, 36, 10', 12', resistor 37^a, 31, 32, 33, to generator. It will be noted that the resistors 34^a, 34^b, and 37^a are in series, and the motor 14 therefore operates at fractional speed.

When the drum is moved further to the right to the position marked "hand 2," the energizing circuit of the magnet 7 is maintained, but the contact 59 of the drum-switch now engages 66, and the contact 60 engages 125 68. The actuating circuit of the motor 14 is now from generator 17, through 21, 22, 23, 75, 67', 62, 59, 66, 77, 34^b, 11, 9, 35, motor 14, 36, 10', 12', to 78. From this point two circuits are established,—one through the re- 130

sistor 37^a and by 31, 32 and 33 to generator, and the other through 79, 80, 68', 63, 81, 60, 68, 82, resistor 37^b, 31, 32, 33 to generator. Furthermore, a portion of the current 5 tending to energize the motor 14, when the drum switch is in the position marked "hand 2," would flow through the resistor 34^a in parallel with the circuit through the drum switch to the resistor 34^b, already traced. The fact that the resistor 34^a has a shunt 10 circuit around it, and that the resistors 37^a and 37^b are in parallel, greatly decreases the resistance in series with the motor armature, and correspondingly increases its speed. When the drum switch is returned to the "off" position, the magnet 7 is deenergized, and the switch S returns to its normal position, thereby short circuiting the motor 10 and applying a dynamic brake in the manner 20 already described.

When the drum switch is moved to the left, or "raise" direction, the magnet 8 is energized, operating the switch S', and establishing similar circuits to those already 25 traced. With certain types of winding mechanism it is necessary to either operate the mechanism at different speeds in the two different directions, or where the regulator resistance to movement is greater in one direction than it is in the other, it is necessary, in order to obtain the same speed in the opposite direction, to provide different amounts of resistance in the motor circuit in the different directions. In the foregoing 30 description, and from the drawing, it will be noted that when the switch S is closed, both sections of the resistances 34^a and 34^b are in series with the motor 14, while when the switch S' is closed, only the section 34^a is 40 inserted.

The energizing circuit of the motor 14 has been traced in connection with the position "hand 2" at the right. When the drum switch is at "hand 2" at the left, the energizing 45 circuit of the motor is as follows: from generator 17, through 21, 22, to wire 23. At this point the circuit divides, a part going through resistor 34^a to wire 77, and a part going through 23, 75, 67', 84, 67, 62, 59', 66', 50 85, 34^b, to wire 77, thence through contacts 11' and 9', 36, motor 14, 35, 10 and 12. At this point the circuit divides, part going 55 through resistor 37^b, 31, 32, 33 to generator, and the other through 82, 68, 63, 81, 60', 68', 78, resistor 37^a, 31, 32, 33 to generator. Resistors 37^a and 37^b will, therefore, be in parallel.

A still further increase in speed on position "hand 2" to the left, may be obtained 60 by connecting contact 66' to contact 77, and eliminating conductor 85, thus eliminating any portion of resistor 34 from the circuit on this position. The connection of the wires 77 and 31 to the respective resistors, 65 may be adjusted so that the relative amount

of resistance in each arm or branch may be regulated to provide for varying speeds of the motor, as desired.

The solenoids 43' and 42' operate in substantially the same manner as the solenoids 42 and 43, already described in connection with Fig. 1. When the solenoid 52 actuates the walking beam 2 to close the contacts 4 and 6, the magnet 8 is actuated, and the switch S' is moved so as to complete the circuit to the motor 14, as already described. The solenoid 42' is energized proportionally to the counter electro-motive force developed in the armature of the motor 14, by wire 36, 88, solenoid 42', 89, 82, 12, 10, and 80 35, back to the motor. The solenoid 42' tends to oppose the solenoid 52, and thus tends to open the contacts 4 and 6 more promptly than would be the case if such action were absolutely dependent upon the 85 decreasing current in the solenoid 52, due to the readjustment of the electrode position. The reactive force, however, is sufficient to open the contacts 4-6, or 4-5, only when smaller changes are indicated by the plunger. The solenoid 52 is not, in itself, sufficient to open these contacts where larger changes of power are shown by the indicating mechanism. In other words, the reactive or anti-hunting device is so proportioned that it would not interrupt or slow down the speed of the winding motor when great changes are to be regulated. At the same time, it is adjusted so as to quickly interrupt or slow down the winding motor 90 speed when minimum changes are to be regulated, and interrupt or slow down the winding motor speed to proportional velocities for intermediate changes. When the solenoid 52 operates the walking beam in 105 the opposite direction to close the contacts 4-5, the reacting coil 43' is then energized in such a manner as to assist the pull of the solenoid, thus effecting a more prompt stopping of the motor to eliminate hunting or 110 overrunning.

If the power supply to the transformer 51 should fail from any cause, the circuit breaker 70 would operate to break the circuit through the regulator, thus obviating 115 the danger of a sudden rush of heavy current through the electrode when restarting the furnace, which might be immediately submerged in the bath by the regulating device, were not the latter put out of commission by the circuit breaker.

A regulator constructed and arranged as described above has the advantage of great simplicity, instant starting of the winding motor, and instant stopping. A difficulty 125 often experienced in regulators is their tendency to hunt or overrun, and this danger is entirely obviated by my improved apparatus, thus permitting more rapid adjustments to be made by the regulator. The facility 130

with which the mechanism is governed, either automatically or by hand, is another feature of importance. The provision of means by which the motor may be controlled 5 so as to operate in either direction at fractional or part speed, renders the device particularly desirable in those cases where, as already pointed out, it is advantageous to operate at one speed in one direction and at 10 a different speed in the opposite direction.

It is obvious that a governor responsive to variations of velocity, voltage, pressure, quantity, or other variable, as well as power, might be used, and also that the regulator 15 might be employed for other purposes than those disclosed herein, without departing in the least from the spirit and the scope of the invention.

I claim:

20 1. A regulator, comprising a governor having a movable element, a source of current, a motor, means controlled by the governor for connecting the motor with the source of current, and electro-magnetic 25 means comprising two independent oppositely acting portions connected with said motor for exerting a reactive force on said governor element.

20 2. A regulator, comprising a governor having a movable element, a source of current, a motor, means controlled by the governor for connecting the motor with the source of current, and electro-magnetic 35 means comprising two independent oppositely acting portions connected with said motor for exerting a reactive force on said governor element, said reactive force being substantially proportional to the counter electro-motive force of the motor.

40 3. A regulator, comprising a governor having a movable element, a source of current, a motor, means controlled by the governor for connecting said motor to and disconnecting it from said source of current, 45 and means for preventing the overrunning or hunting of the motor including two separate electro-magnetic means connected with said motor, and disposed to urge the movable element in opposite directions, for exerting a reactive force on said governor element.

45 4. An electric regulator, comprising a governor, a source of current, a motor, auxiliary means controlled by said governor for connecting or disconnecting said motor from said source of current, and manual means comprising a switch operative in one position to throw the governor into circuit with the auxiliary means, whereby automatic control is secured, and operative in other positions to provide independent manual control of said auxiliary means.

50 5. An electric regulator, comprising a governor, a source of current, a motor, a pair 55 of magnets controlled by said governor, a

switch actuated by each magnet for connecting or disconnecting said motor, and manual means comprising a switch operative in one position to throw the governor into circuit with the magnets, whereby automatic control 70 is secured, and operative in other positions to provide independent manual control of said magnets.

6. An electric regulator, comprising a governor, a source of current, a motor, circuit 75 connections between said source of current and said motor, said circuit connections including resistors, a pair of magnets controlled by said governor, a switch actuated by each magnet and arranged to form part 80 of the motor circuit, and a manual controlling switch for controlling said magnets independently of the governor, said switch in one position being operative to throw the governor into circuit whereas in other positions it is operative to directly manually 85 control the magnets and to disconnect the governor from the circuit.

7. An electric regulator, comprising a governor, a source of current, a motor, circuit 90 connections between said source of current and said motor, said circuit connections including resistors, auxiliary means controlled by said governor for controlling the said circuit connections, a manually operated 95 switch having a plurality of contacts for independently controlling said auxiliary means and for determining the amount of resistance brought into the motor circuit.

8. An electric regulator, comprising a gov- 100 ernor, a source of current, a motor, means actuated by said governor for connecting said source of current with said motor, resistors in said motor circuit, and manual means for determining the amount of re- 105 sistance brought into the motor circuit, whereby the speed of the motor may be varied.

9. An electric regulator, comprising a gov- 110 ernor, a source of current, a motor, means actuated by the governor for connecting and disconnecting said motor from said source of current, and manual means for controlling said last named means independently 115 of the governor, said manual means being movable to different positions to vary the direction of rotation or the speed of the motor.

10. In an electric regulator, a governor, a source of current, a motor, means actuated 120 by said governor for connecting and disconnecting said motor from said source of current, an auxiliary electro-magnetic device for aiding the movement of the governor in one direction, and a second electro-magnetic 125 device for aiding the movement of the governor in the opposite direction, and circuits connecting the said auxiliary electro-magnetic devices to the motor circuits whereby said devices are actuated in response to 130

the direction and value of the counter electromotive force of the motor.

11. In an electric regulator, a governor, a source of current, a motor, means actuated by said governor for connecting and disconnecting said motor from said source of current, an auxiliary electro-magnetic device for aiding the movement of the governor in one direction, and a second electro-magnetic device for aiding the movement of the governor in the opposite direction, said electro-magnetic devices being selectively connected with said motor and operating with a force substantially proportional to the speed or counter electro-motive force of the motor.

12. In an electric regulator, a governor, a source of electricity, a motor, a switch actuated by said governor, a pair of electro-magnetic devices controlled by said switch, and two single-pole double-throw switches, each operated by a corresponding one of said electromagnetic devices, said motor being normally short-circuited through both of said single-pole double-throw switches, an electromagnetic means coöperating with said governor to actuate it in response to variations of electrical condition of said means, and reactive means adapted to be electrically connected in circuit with said source of electricity and said motor by the said single-pole double-throw switches to exert a force on the governor which is a function of the counter electromotive force of said motor.

13. In an electric regulator, a governor, a source of electricity, a motor, a switch actuated by said governor, a pair of electromagnetic devices controlled by said switch, and two single-pole double-throw switches, each operated by a corresponding one of said electromagnetic devices, said motor being normally short-circuited through both of said single-pole double-throw switches, an electromagnetic means coöperating with said governor to actuate it in response to variations of electrical condition of said means, and reactive means adapted to be electrically connected in circuit with said source of electricity and said motor by the said single-pole double-throw switches to exert a force on the governor which is a function of the counter electromotive force of said motor, the said force being always so directed as to oppose the existing tendency of the governor to change its position.

14. In an electric regulator, a governor, a source of electricity, a motor, a switch actuated by said governor, a pair of electromagnetic devices controlled by said switch, and two single-pole double-throw switches, each operated by a corresponding one of said electromagnetic devices, said motor being normally short-circuited through both of said single-pole double-throw switches, the operation of either one of the last named switches serving to remove the short-circuit,

one serving to complete the circuit from the source of electricity through the motor in one direction, and the operation of the other switch serving to reverse the circuit through one element of the motor, an electro-magnetic means coöperating with said governor to actuate it in response to variations of electrical condition of said means, and reactive means adapted to be electrically connected in circuit with said source of electricity and said motor by the said single-pole double-throw switches to exert a force on the governor which is a function of the counter electromotive force of said motor.

15. In an electric regulator, a governor, a source of electricity, a no-voltage relay co-operating with said source of electricity to open the circuit when the current fails, a motor, a switch actuated by said governor, a pair of electromagnetic devices controlled by said switch, and two single-pole double-throw switches, each operated by a corresponding one of said electromagnetic devices, said motor being normally short-circuited through both of said single-pole double-throw switches, an electromagnetic means coöperating with said governor to actuate it in response to variations of electrical condition of said means, and reactive means adapted to be electrically connected in circuit with said source of electricity and said motor by the said single-pole double-throw switches to exert a force on the governor which is a function of the counter electromotive force of said motor.

16. An electric regulator comprising a governor, a source of current, a motor, means controlled by said governor for connecting said motor to or disconnecting it from said source of current so as to start, stop and reverse the same, and a manual drum switch for controlling said motor independently of the governor, said switch in one position serving to vest the control of the motor in said governor, and in other positions serving to deprive the governor of such control and itself manually control the motor directly.

17. In an electric regulator, a governor, a source of current, a motor, a switch actuated by said governor, a pair of electro-magnetic devices controlled by said switch, and manual means for independently controlling said devices, said last named means comprising a drum switch, and contacts carried by said drum switch, certain of said contacts leading to the first named switch, and others leading to the circuits of the electromagnetic devices directly, whereby the drum switch in one position throws the governor into circuit, whereas in other positions the governor is disconnected from the circuit, and the electromagnetic devices are controlled manually only.

18. In an electric regulator, a power circuit, a no-voltage relay in said circuit, a motor-generator set, a fly-wheel connected with said motor-generator set, a motor, a 5 governor, a switching device including switch operating means controlled by said governor for connecting the motor with the generator, electro-magnetic means connected with said motor for exerting a reactive force 10 on said governor, and a hand operated switch serving in one position to connect the governor into the control circuit, and in other positions disconnecting the governor from said circuit and itself serving as 15 a manual control device for independently actuating said switch operating means.
19. A regulator, comprising a governor, having a movable switch arm, a source of current, a motor, means actuated by the 20 governor for connecting the motor with the source of current, a pair of opposed solenoids coöperating with the switch arm, and connections between the solenoids, and the motor whereby the solenoids are actuated.
- 25 20. Apparatus for regulating electric arc furnaces comprising an electrode to be shifted, a power circuit through said electrode, an electric motor operatively connected to said electrode, a pair of switches 30 for starting, stopping and reversing said motor, a governor responsive to variations of energy in the electrode circuit for controlling said switches, and two separate means, each comprising a circuit including 35 respectively one of said switches, for automatically modifying the effective action of said governor after the same has responded to a variation of energy, whereby hunting is reduced.
21. Apparatus for regulating electric arc 40 furnaces comprising an electrode to be shifted, a power circuit through said electrode, an electric motor operatively connected to said electrode, a pair of switches for starting, stopping, and reversing said 45 motor, an electromagnetic governor responsive to variations of energy in the electrode circuit for controlling said switches, and two separate means, each including respectively one of said switches, for automatically decreasing the effective force actuating said electromagnetic governor after the same has responded to a variation of energy. 50
22. Apparatus for regulating electric arc 55 furnaces comprising an electrode to be shifted, a power circuit through said electrode, an electric motor operatively connected with said electrode, a pair of single-pole double-throw switches for starting, stopping, and reversing said motor, the arrangement being such that either of said switches when thrown in one direction starts the motor, and when thrown in the other direction stops the motor, the motor armature being normally connected in a circuit closed on itself through both of said switches, independent electromagnetic means for operating said switches, a governor responsive to variations of energy in the electrode circuit for selectively controlling said 60 electromagnetic means, and two separate means, each including respectively one of said switches, for automatically modifying the effective action of the governor after the same has responded to a variation of 65 energy. 70

In testimony whereof I affix my signature.
WILLIAM E. MOORE.
